[57] CLAIM

The ornamental design in a paint tray or the like, as shown and described.

DESCRIPTION

FIG. 1 is a perspective view of a paint tray or the like showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a side elevational view thereof;

FIG. 7 is an elevational view of the opposite side thereof;

FIG. 8 is a sectional view thereof taken along line VIII—VIII of FIG. 2;

FIG. 9 is a perspective view of a second embodiment of the design shown in FIG. 1, the only difference being the exclusion of the cylindrical applicator;

FIG. 10 is a top plan view thereof;

FIG. 11 is a front elevational view thereof;

FIG. 12 is a rear elevational view thereof;

FIG. 13 is a side elevational view thereof;

FIG. 14 is an elevational view of the opposite side thereof; and,

FIG. 15 is a sectional view taken along line XV—XV of FIG. 10.

The bottom plan view of the second embodiment is identical to that shown in FIG. 4.

FIG. 1
